ABSTRACT

The invention provides, as new compounds, salts of certain bactericidally active bis-biguanides bases with sequestering amino-carboxylic acids, the compounds being useful as bactericides. The invention also provides compositions containing these salts; the compositions preferably incorporate quaternary ammonium compounds as solubilizing agents for the salts.

1 Claim, 4 Drawing Figures

BIS-BIGUANIDES

This invention concerns novel bis-biguanides, processes for their preparation, and compositions incorporating them. More specifically, the invention relates to certain novel bis-biguanide salts which appear to have interesting bactericidal properties, and which may thus be of use in human or veterinary medicine.

Bis-biguanides are known (in general) to have certain bactericidal properties, and one such compound in particular - 1,6-bis-(N₁-p-chlorophenylbiguanido-N₅)-hexane, which has the open name "chlorhexidine" - has found considerable use in medicine as a bactericide, and primarily as a general disinfectant. Unfortunately, however, the known bis-biguanide bases - and most of their salts - are only sparingly soluble in water (which is the solvent of choice for making up disinfectant compositions), and therefore have a limited use from a commercial point of view.

We have now found that a new class of bis-biguanide salts can be dissolved in water more easily than most known salts, and is more active than all known salts - and thus these compounds are more useful as disinfectants in particular and bactericides in general.

In one aspect, therefore, this invention provides a salt of a known bactericidally active bis-biguanide base with a sequestering amino-carboxylic acid falling within the general formula:

(II)

wherein:

R¹ represents hydrogen, an alkyl group, a carboxymethyl group, a hydroxyethyl group or a hydroxypropyl group;

R² represents a carboxymethyl group, a hydroxyethyl group or a hydroxypropyl group; and

either Z represents the group - [CH₂.CH₂.N(R³)]_n (wherein R³ is defined as R¹, though is not necessarily identical thereto, and n is 0,1,2 or 3), or Z represents the group

(III)

(wherein R³ is as defined hereinbefore), subject to the proviso that, when n is 1 R₁, R₂ and R₃ are carboxymethyl groups.

Typical amino-carboxylic acids falling within general formula II are:

N,N'-ethylenediaminediacetic acid (EDDA) - n = 1, R¹ and R³ = hydrogen, and R² = carboxymethyl;

N-hydroxyethylenediaminetriacetic acid (HEDTA) - n = 1, R¹ and R² = carboxymethyl, and R³ = 2-hydroxyethyl;

N,N'-dihydroxyethylenediaminediacetic acid (HEDDA) - n = 1, R¹ and R² = 2-hydroxyethyl, and R³ = carboxymethyl;

diethylenetriaminepentaacetic acid (DTPA) - n = 2, and R¹, R² and both R³'s = carboxymethyl;

1,2-diaminocyclohexanetetraacetic acid (CDTA) - R¹, R² and R³ = carboxymethyl;

nitrilotriacetic acid (NTA) - n = 0, and R¹ and R² = carboxymethyl;

N-hydroxyethyliminodiacetic acid (HIMDA) - n = 0, R¹ = 2-hydroxyethyl, and R² = carboxymethyl;

N,N-dihydroxyethylaminoacetic acid (DAA) - n = 0 and R¹ and R² = 2-hydroxyethyl;

iminodiacetic acid (IMDA) - n = 0, R¹ = hydrogen and R² = carboxymethyl; and

3-hydroxypropyliminodiacetic acid (HPIMDA) - n = 0, R¹ = 3-hydroxypropyl, and R² = carboxymethyl.

Of these particular aminocarboxylic acids, HEDTA DTPA, NTA and DAA are preferred, and HEDTA and DAA are especially preferred.

The salts of this invention - the compounds may essentially be regarded as the reaction product between the acidic sequestering amino-carboxylic acid and the basic bis-biguanide (and can, thus, be referred to generally not only as "salts" but also as "sequestrates") - may contain the two compounds (the acid and the base) in varying proportions, because the acids are mostly poly-acidic (they have two or more acid groups) and chlorhexidine is dibasic, and because all of the basic/acidic groupings may not necessarily be "used up." However, in general (but not always) the acidic amino-carboxylic acids tend to act either as mono-acidic acids or as di-acidic acids (wherein either one or two acidic groupings are used).

Thus, for example, the particularly preferred amino-carboxylic acid HEDTA acts either in a mono- or di-acidic fashion, and - so far as can be determined - the only salts formed are chlorhexidine mono-HEDTAcetate (wherein the HEDTA is di-acidic) and chlorhexidine di-HEDTAcetate (wherein the HEDTA is mono-acidic).

Of the various salts (sequestrates) obtainable using the preferred amino-carboxylic acids listed above, the particularly preferred ones are:

mono-chlorhexidine nitrilotriacetate (chlorhex/NTA);

tri-chlorhexidine di-[diethylenetriaminepentaacetate] (3 chlorhex/2 DTPA);

mono-chlorhexidine di-[N,N-dihydroxyethylaminocetate] (chlorhex/2 DAA); and, especially,

mono-chlorhexidine N-hydroxyethylethylene-diaminetriacetate (chlorhex/HEDTA), and mono-chlorhexidine di-[N-hydroxyethyl-

thylene-diaminetriacetate] (chlorhex/2 HEDTA).

The sequestrates of this invention may be made by any of the conventional methods employed for the preparation of salts. In particular, they may be prepared by a straight acid/base reaction, or they may be prepared by a metathesis (or double decomposition) reaction between another salt of the acid and another salt of the base.

Accordingly, in another aspect this invention provides a process for the preparation of a bis-biguanide/amino-carboxylic acid sequestrate of the invention, in which chlorhexidine (or salt thereof) is reacted in an aqueous medium with an appropriate amino-carboxylic acid (or salt thereof) to give the desired sequestrate.

While the amino-carboxylic acids (and their salts) are in general water-soluble, the bis-biguanide (and its salts) tend to be not very soluble in water. Accordingly it is preferred that the reaction be effected in the pres-

ence of a medium in which the bis-biguanide is soluble, which medium is easily miscible with the water present. Such mediums are the alkanols, and particularly suitable alkanols are methanol and ethanol. Thus, the reaction is preferably effected in aqueous methanol or ethanol.

Of course, both the bis-biguanide and the amino-carboxylic acid may be dissolved in the aqueous alkanol, or the former may be dissolved in alkanol, the latter in water, and the two solutions mixed.

When effecting the reaction using a salt of the bis-biguanide and a salt of the amino-carboxylic acid (metathesis) the former is preferably one of these with common organic acids (for example, the diacetate) and the latter is preferably an alkali-metal salt (for example, a sodium salt). Mineral acid bis-biguanide salts are to be avoided since they are extremely water-insoluble.

The formed salts may be isolated by conventional techniques, but for some purposes they need not be isolated at all (the prepared solution containing them may be used as it is), and this is discussed hereinafter.

As stated above, the novel bis-biguanide sequestrates of this invention appear to exert a useful anti-bacterial activity. Now, while the bis-biguanides of general formula I are known to have anti-bacterial activity in salt form, the sequestrates derived from them have a greater anti-bacterial activity - and this can be manifest in several ways. Firstly, the spectrum of activity of the bis-biguanide salts at a given concentration can be "extended"; that is to say, a given bis-biguanide salt may be inactive against a particular species of bacteria at a given concentration, whereas a corresponding sequestrate will be active when applied at the same concentration expressed in terms of the bis-biguanide base. Secondly, if a particular concentration of a bis-biguanide salt is needed to kill a bacterial culture, then a lower concentration of a corresponding sequestrate may be needed to have the same killing power. Thirdly, since many of the known salts of the bis-biguanides are only moderately soluble in water, it may be possible to reach a greater concentration in terms of bis-biguanide base using the more soluble sequestrates.

However, before any of the sequestrates of this invention may be used in medicine, they should preferably be formed into compositions by association with suitable vehicles. Naturally, the term "suitable vehicle" is used herein to exclude any possibility that the nature of the vehicles, considered of course, in relation to the use to which the composition is to be put, could be harmful rather than beneficial. The choice of a suitable mode of presentation, together with an appropriate vehicle, is believed to be within the competence of those accustomed to the preparation of pharmaceutical and other formulations.

Accordingly, in yet another aspect, this invention provides compositions containing one or more bis-biguanide sequestrates of the invention, in association with a suitable vehicle.

The type of vehicle employed, and thus the nature of the composition, will depend largely on the purpose for which the composition is to be used. For example, probably by far the most important use of the compositions will be as disinfectants, primarily for use in hospitals, and as such the composition will generally be liquid, the vehicle being, for instance, water. However, the sequestrates may well find other uses (not only in medicine but also in any field where a bactericide is re-

quested - such as in the food trade), and indeed in some respects they seem adapted not only for use as disinfectants of inanimate objects (bed linen, walls, tables, pots, pans and so forth - equipment in general) but also as antiseptics on or in humans and other animals. Thus, in general the compositions of this invention may be "administered" orally, perlingually, topically, or rectally, and in respect of these modes, the "vehicle" is preferably:-

- 10 a. the ingestible excipient of a tablet, coated tablet, sublingual tablet or pill; the ingestible container of a capsule or cachet; the ingestible pulverulent solid carrier of a powder; or the ingestible liquid medium of a syrup, solution, suspension or elixir;
- 15 b. the solid or liquid carrier medium of an ointment, paste, gel, salve, lotion, balm, unguent, wash, cream, solution, emulsion or dusting powder;
- c. a base material of low melting point capable of releasing an active ingredient to perform its pharmaceutical function, which base material when appropriately shaped forms a suppository.

Whilst the modes of presentation just listed represent those most likely to be employed, they do not necessarily exhaust the possibilities.

25 The compositions of this invention that are prepared by formulating an isolated sequestrate will, naturally, contain the two moieties involved - the bis-biguanide moiety on the one hand, and the amino-carboxylic acid moiety on the other hand - in stoichiometric molar proportions. Thus, for example, a composition made from chlorhex/HEDTA contains the two moieties in the molar ratio 1:1, while a composition made from chlorhex/2 HEDTA contains the two moieties in the molar ratio 1:2.

30 35 It is possible, however, to make up compositions containing an "excess" of either moiety (or, rather, containing an additional quantity of either the bis-biguanide itself or the amino-carboxylic acid itself), and in many cases the use of an excess - particularly an excess of amino-carboxylic acid - is advantageous and appears to give rise to somewhat better bactericidal properties than might be expected. With the amino-carboxylic acid, for example, excesses of the order of half a mole per mole of bis-biguanide give compositions which perform quite satisfactorily.

40 45 The sequestrates of this invention, though in general all highly active as bactericides, are not all equally soluble in water. Indeed, some of them are so poorly soluble that it is difficult, if possible at all, to form a liquid aqueous composition that contains enough sequestrate to act properly as a bactericide without using a solubilizing agent (discussed hereinafter). Accordingly, this invention does not extend to sequestrate-containing compositions which are aqueous and liquid, and which do not incorporate a solubilizer, where the sequestrate is incapable, without the aid of a solubilizer, of being dissolved in water to a concentration of more than 1000 ppm.

50 55 60 65 In order to prepare a commercially attractive liquid aqueous composition according to the invention (as opposed to a composition which works, as a bactericide, though rather poorly) it is necessary to be able to prepare and sell a concentrate, and thus to dissolve large quantities of the sequestrate (and by "large quantities" are meant amounts of from 1 percent by weight of the composition upwards). In order, therefore, to ensure that the compositions of the invention meet this

criterion it is highly desirable that they should contain, in addition, a solubilizing agent for the sequestrate, and a class of solubilizing agents which is particularly suitable (partly because most of the agents are themselves bactericidal, partly because the agents have detergent properties useful in a disinfectant composition and partly because, as is discussed below, the thus-formed compositions appear to exhibit synergism) is the quaternary ammonium compounds.

Of the very large number of available quaternary ammonium compounds (QACs) the following seem preferable:

those having a cation of the general formula

(wherein:

Y^1 is an alkyl group containing from 8 to 20 carbon atoms, a di-isobutyl-phenoxy-ethoxyethyl group, or a diisobutyl-cresoxyethoxyethyl group; and

Y^2 is an aralkyl group, preferably a benzyl group, optionally substituted in the aromatic nucleus) especially those having the "benzalkonium" cation (which is described in the literature as alkylidimethylbenzyl ammonium wherein the alkyl is the well known "coco" group being a mixture of alkyl groups mainly in the C_{10} - C_{18} range such as lauryl, myristyl, etc.), and the compounds sold under the trade names Hyamine LOX and Hyamine 1622 in the USA (which are described as having the cations di-isobutylcresoxyethoxyethyl dimethyl benzyl ammonium and di-isobutylphenoxyethoxyethyl dimethyl benzyl ammonium), and the myristyldimethylbenzyl ammonium compounds;

those having a cation of the general formula

(wherein:

Y^3 is either an alkyl group containing from 8 to 18 carbon atoms or an alkylbenzyl group in which the alkyl moiety contains from 8 to 20 carbon atoms), especially the cetyltrimethyl ammonium compounds such as the bromide known under the open name of "cetrimide";

those having a cation of the general formula

(wherein:

Y^4 and Y^5 , which may be the same or different, are each an alkyl group containing from 8 to 18 carbon atoms), especially the didecyldimethyl ammonium and the dioctyl-dimethyl ammonium cations;

those having a cation of the general formula

5

wherein:

Y^6 is an alkyl group of 8 to 20 carbon atoms; and

Y^7 and Y^8 are the same or different, and each is a hydroxy-substituted alkyl or hydroxyalkoxyalkyl group), especially alkyl dihydroxyethyl) benzyl ammonium, wherein the alkyl is, for example, a "coco" group; and those having a cation of the general formula

15

(wherein: Y^9 is an alkyl group of 8 to 20 carbon atoms),

25 especially the cetylpyridinium cation.

The particularly preferred quaternary ammonium cations are benzalkonium, myristyldimethylbenzyl ammonium, cetyltrimethyl ammonium, and coco dihydroxyethyl)benzyl ammonium.

30 Incidentally, it does not seem to matter very much what anion is associated with the quaternary ammonium cation. Nevertheless, the hydroxides, chlorides and bromides are preferred.

The proportions in which the quaternary ammonium 35 compound may be used to solubilize the sequestrate depend to a considerable degree on the particular quaternary, the particular bis-biguaine in the sequestrate, and the particular amino-carboxylic acid in the sequestrate. Accordingly it is difficult to give hard-and-fast

40 rules about how much quaternary is required to solubilize how much sequestrate. Nevertheless, by way of general indication it may be said that a good solubilizing quaternary - for example, Cetrimide (cetyl trimethyl ammonium bromide) - can solubilize as much

45 sequestrate as will give a 20 percent by weight aqueous solution, and at that level is solubilizing on an equal weight basis (whereas at lower concentrations of sequestrate the quaternary tends to solubilize slightly more than its own weight). A not-so-good solubilizing quaternary may only solubilize as much sequestrate as will give a 5 percent solution, and at that level may be solubilizing perhaps only 1/10 its weight of sequestrate.

A few general examples of maximum solubilizing 50 power of various quaternary ammonium compounds with various bis-biguaine sequestrates are as follows (the percentages are by weight based on the final solution, and the formed solutions were stable):

55 18 percent centrimide solubilizes 27 percent chlorhex/HEDTA;

30 percent benzalkonium chloride solubilizes 15 percent chlorhex/HEDTA;

20 percent benzalkonium bromide solubilizes 20 percent chlorhex/HEDTA;

20 percent centrimide solubilizes 30 percent chlorhex/NTA;

20 percent centrimide solubilizes 30 percent 3 chlorhex/2 DTPA.

60

In any given case the solubilizing power of a particular quaternary to a particular sequestrate may easily be determined by trial.

As stated above, one of the reasons for choosing quaternary ammonium compounds as the solubilizing agents is that not only are the quaternaries usually bactericidal in their own right but also there appears to be synergistic action between the quaternary and the sequestrate, the bactericidal activity of the composition being greater (in some cases considerably greater) than might be expected from a simple summation of the activities of the two components. Of course, it is in marginal cases difficult to be sure that synergy occurs - but, as is pointed out hereinafter in connection with the Test Results, in some cases there would seem to be no such difficulty.

The compositions of this invention may be made simply by mixing the sequestrate with the vehicle (and with excess sequestrate moiety and/or with quaternary ammonium compound as appropriate). However, as intimated above the formed sequestrates need not necessarily be isolated from their reaction media; the reaction solution may well constitute a suitable aqueous liquid composition.

It follows, therefore, that compositions of this invention can be prepared simply by dissolving the bisbiguanide and the amino-carboxylic acid in water or an aqueous alkanol - to which also may be added (if desired) the quaternary ammonium compound.

Furthermore, because of the ability of the quaternary ammonium compounds to form salts with the amino-carboxylic acids (the salts being quaternary ammonium sequestrates), it is also possible to form compositions of this invention by dissolving in water or an aqueous alkanol the bis-biguaine and the quaternary ammonium sequestrate.

Examples of these various procedures are given hereinafter.

The following Examples are now given, though by way of illustration only, to show details of preferred compounds, preparative processes and compositions according to this invention.

PART I: PREPARATION OF BIS-BIGUANIDE SEQUESTRATES

**EXAMPLE 1: Mono(chlorhexidine)
mono(hydroxyethylenediamine triacetate)**

Method A

2.66 gm of chlorhexidine base and 1.40 gm of hydroxyethylethylenediaminetriacetic acid were dissolved together in 50 ml of distilled water with heating. Thus, the acid and base were present in approximately equimolar proportion. The resultant solution was allowed to cool and after a few hours a white precipitate came down. The precipitate was filtered, washed and dried to give the mono(chlorhexidine) mono(hydroxyethylethylenediaminetriacetate. The pH of the mother liquor was 7.3, and its solubility was 0.2 percent w/w at 20°C, as measured by the technique described in Example 1.

Method B

25 ml of a 0.01 M solution of chlorhexidine in methanol (thus, 0.1263 grammes of chlorhexidine) were added to 0.0695 gm of HEDTA in 35 ml of distilled water. Thus, the acid and base were present in equimolar proportions. This solution was evaporated to half vol-

ume on a steam bath, then allowed to cool slowly and, after standing for about 2 hours, crystallization was initiated by scratching the side of the vessel with a glass rod. The precipitate was filtered and dried, to give the required salt.

Method C

1 Gm of chlorhexidine diacetate was dissolved in 25 mls of industrial methylated spirit, and was added to a solution of 0.4448 grams of HEDTA in 3.2 mls of normal sodium hydroxide and 5 mls of distilled water. Thus, the acid and base were present in equimolar proportions. A precipitate formed on standing which was filtered, washed with distilled water and dried to give the desired compound.

In each case, a differential scanning calorimeter showed that salt formation had occurred. This was confirmed by the melting points, which were as follows:

<u>Melting Points</u>	
HEDTA	156°C
Chlorhexidine	127°C
Salt (Methods A and B)	173°C
(Method C)	177°C
Physical mixture of acid and base	124°C

EXAMPLE 2: Mono(chlorhexidine) di(hydroxyethylenediaminetriacetate)

30 1.33 G of chlorhexidine and 1.42 g HEDTA were dissolved together in 25 ml distilled water by heating. Thus, the molar ratio of base to acid was 1:2. The solution was cooled, whereupon a white precipitate formed, which was filtered, washed and dried to give 35 mono(chlorhexidine) di(hydroxyethylethylenediaminetriacetate). The pH of the mother liquor was 6.1, the melting point of the salt was 172°C and its solubility in water was 0.3 percent w/w at 20°C.

**EXAMPLE 3: Mono(chlorhexidine)
mono(nitrilotriacetate)**

25 ml of a 0.04 M solution of chlorhexidine diacetate in distilled water were added to 25 ml of a 0.04 M solution of disodium nitrilotriacetate in distilled water.

45 Thus, the acid and base were present in equimolar proportions. A fine, oily precipitate was formed which at first remained suspended in the liquid, but which solidified on standing. This precipitate was filtered, washed with distilled water and dried to give mono(chlorhexidine) mono(nitrilotriacetate). The solubility of the salt in water at 20°C is 0.3% w/w,

A differential scanning calorimeter confirmed the formation of the salt and this was further verified by melting point tests, which gave the following melting points:

60	NTA Chlorhexidine Salt Physical Mixture of NTA and chlorhexidine	225°C 127°C 176°C 129°C

EXAMPLE 4: Tri(chlorhexidine) di(diethylenetriaminepentaacetate)

65 0.69 G of diethylenetriaminepentaacetic acid was dissolved in 100 ml of distilled water by heating. 1.33 g of chlorhexidine was dissolved in this solution by heating and stirring. Thus, the base and acid were pres-

ent in a molar ratio of 3:2. After cooling an oil separated, but after two days at room temperature all the oil had turned into white crystals. The crystals were recrystallized in water, dried at 100°C to constant weight, to give tri(chlorhexidine) di(diethylenetriaminepentacetate). This compound had a melting point of 157°C and a solubility in water of 0.2 percent w/w at 20°C.

**EXAMPLE 5: Mono(chlorhexidine)
di(dihydroxyethylaminoacetate)**

100 ml of a 2 percent solution of chlorhexidine diacetate in distilled water were added to a solution of 1.234 g of the monosodium salt of dihydroxyethylaminoacetic acid (equivalent to 1.0432 grammes of dihydroxyethylaminoacetic acid) in distilled water. Thus the chlorhexidine cation and the dihydroxyethylaminoacetic acid anion were present in a molar ratio of 1:2. The precipitate was filtered, washed and dried, to give mono(chlorhexidine) di(dihydroxyethylaminoacetate). The solubility of this salt in water 0.2 percent w/w at 20°C.

A differential scanning calorimeter showed the formation of the salt, and this was confirmed by melting point tests, which gave the following melting points:

Dihydroxyethylaminoacetic acid	180°C
Chlorhexidine	127°C
Salt	86°C
Physical Mixture	107°C

Part II: Compositions without quaternary ammonium compounds

**EXAMPLE 6. Mono(chlorhexidine)
di(hydroxyethylethylenediaminetriacetate)**

a. Preparation of the compositions

Solid mono(chlorhexidine) di(hydroxyethylethylenediaminetriacetate), prepared as in Example 2, was dissolved in standard hard water (W.H.O. formulation - see below) to yield solutions containing 400, 600, 800, 1200, 1600, 2000 and 2500 ppm of the salt.

b. Bactericidal Tests

The solutions prepared in a) were tested for bactericidal activity according to British Standard No. 3286: 1960 (see the publication "Method for laboratory evaluation of disinfectant activity of quaternary ammonium compounds by suspension test procedure," published by the British Standard Institution, British Standards House, 2 Park Street, London, S.W.1. London, 1960).

Many anti-bacterial compositions are less active against gram negative bacteria than against gram positive bacteria. Furthermore, their anti-bacterial activity is reduced in the presence of hard water and/or organic matter such as blood serum.

Thus a particularly stringent anti-bacterial test is one against the highly resistant gram negative bacterium, *Pseudomonas pyocyannea* in the presence of hard water.

The essential details of the test procedure are as follows:

i. Materials

Nutrient Broth

Nutrient Broth No. 2 is used which contains:
Lab-lemco (A proprietary brand of proteinaceous material)
Peptone
Sodium Chloride
Distilled water to

10 grams
10 grams
5 grams
1,000 mls.

This autoclaved for 15 minutes at 15 lbs. per square inch pressure (121°C). The final pH is approximately 7.4.

5 Inactivator

Nutrient broth with the addition of 10 percent Lubrol W. (a proprietary brand of a condensation product of a long chain fatty alcohol and ethylene oxide).

10

Standard Hard Water (W.H.O. Formulation)

10% $\text{CaCl}_2 \cdot 6\text{H}_2\text{O}$ (wt/vol)	17.5 mls.
10% $\text{Mg SO}_4 \cdot 7\text{H}_2\text{O}$ (wt/vol)	5.0 mls.
Distilled water	3,300 mls.

15

This is autoclaved at 15 lbs. per square inch pressure for 15 minutes.

Disinfection Time

5 Minutes.

Temperature

22°C.

Test organism

Pseudomas aeruginosa (*Pseudomonas pyocyannea*).

25 N.C.T.C. No. 6749

Organic matter added

10 percent bovine serum.

ii. Preparation of Culture

30 A culture from agar of the organism was prepared in nutrient broth and incubated at 37°C for 24 hours. Daily subcultures were continued, and cultures between the third and seventh generation used for the test. The broth culture of *Pseudomonas pyocyannea* was filtered aseptically before use, or, shaken, allowed to

35 settle for 15 minutes and the supernatant liquor used for the test.

Culture dilution

One part of the broth culture was diluted with 24 parts of Standard Hard Water, that is 4 ml. broth culture was added to 96 ml. of Standard Hard Water. The average count of bacteria in such a dilution is 5×10^7 organisms per ml.

Method of Test

40 Serial double strength dilutions of the anti-bacterial compositions to be tested were made in standard hard water and 2.5 ml. transferred to a sterile test tube. (By serial double strength dilutions we mean that to test a compound at, for example, 500 ppm, one must prepare a strength 1000 ppm since in the following step the volume in the tube is doubled). Starting at zero time 2.5 ml of the diluted bacterial culture suspensions were added to each test tube containing the anti-bacterial composition under test, (the contents of the bacterial culture/anti-bacterial composition mixture were ad-

45 justed to contain 300 ppm hardness). After 5 minutes 1 ml of the bacterial culture mixture from each tube was transferred to a sterile tube containing 9 ml of inactivator. 1 ml of the mixture thus obtained was transferred to an agar plate, and a further 1 ml to a second tube containing 9 ml of inactivator. Similarly 1 ml of the mixture produced in the second tube was transferred to an agar plate and 1 ml to a third tube containing 9 ml of inactivator and so on. The inactivator stopped the further action of the anti-bacterial agent,

50 and each live bacterium left on addition to the activator produces a colony on the agar plate. The number of colonies on each plate was counted, multiplied by the

appropriate dilution factor, and the results expressed as survivors per million bacteria inoculated (on the base of a control using no anti-bacterial agent; an average control gave approximately 2.5×10^7 bacteria per ml solution at zero dilution)

Control examples were also provided using chlorhexidine dihydrochloride and chlorhexidine digluconate to show the superiority of the compositions of the present invention to those containing these conventional bactericides

Results

The results are expressed in Table I below as the number of survivors immediately after the addition of the inactivator, per million bacteria cells inoculated.

Table I

Final concentration of bactericide p.p.m.	200	300	400	600	800	1000	1250
Bactericide							
Mono(chlorhexidine) Di(HEDTA)	21,818	2,909	16	0	0	0	0
Chlorhexidine dihydrochloride (control)	u/c	u/c			insoluble		
Chlorhexidine digluconate (control)	u/c	u/c	u/c	u/c	3,627	1	0

u/c — number of survivors too great to be counted.

These results show that the quantity of mono(chlorhexidine) di(HEDTA) required to kill a given quantity of *Pseudomonas pyocyannea* is markedly less than that of either chlorhexidine dihydrochloride or of chlorhexidine digluconate.

EXAMPLE 7: Mono(chlorhexidine) mono(hydroxyethyl ethylenediaminetriacetate

a. Preparation of the compositions

Solid mono(chlorhexidine) mono(hydroxyethyl ethylenediaminetriacetate, prepared as in Example 1, was dissolved in standard hard water (W.H.O. formulation) to yield solutions containing 400, 800, 1200, 1600 and 2000 ppm of the salt.

b. Bactericidal tests

The solutions prepared in a) were tested for bactericidal activity in the same manner as in Example 6. Control examples were provided using the same concentrations of chlorhexidine digluconate.

Results

The results are shown in Table II below.

TABLE II

Final concentration of bactericide p.p.m.	200	400	600	800	1000
Bactericide					
Mono (chlorhexidine) Mono (HEDTA)	390	0	0	0	0
Chlorhexidine Digluconate (control)	—	—	300	540	26

These results show that the bactericidal properties of mono(chlorhexidine) mono(HEDTA) are markedly superior to those of chlorhexidine digluconate.

EXAMPLE 8: Mono(chlorhexidine) mono(nitrilo-triacetate).

a. Preparation of the compositions

Solid mono(chlorhexidine) mono(nitrilo-triacetate), prepared as in Example 3, was dissolved in standard hard water (W.H.O. formulation) to yield solutions containing 400, 800, 1200, 1600 and 2000 p.p.m. of the salt.

b. Bactericidal Tests

The solutions prepared in a) were tested for bactericidal activity in the same manner as in Example 6. Control examples were provided using the same concentrations of chlorhexidine digluconate.

Results

The results are shown in Table III below.

TABLE III

Final concentration of bactericide p.p.m.	200	400	600	800	1000
Bactericide					
Mono(chlorhexidine) Mono(nitrilotriacetate)	10,000	235	0	0	0
Chlorhexidine Digluconate (control)	—	—	300	540	26

These results show the superiority of mono(chlorhexidine) mono(nitrilotriacetate) to chlorhexidine digluconate as a bactericide.

EXAMPLE 9: Tri(chlorhexidine) di(diethylenetriaminepentaacetate)

a. Preparation of the compositions

Solid tri(chlorhexidine) di(diethylenetriaminepentaacetate) prepared as in Example 4 was dissolved in standard hard water (W.H.O. formulation) to yield solutions containing 400, 800, 1200, 1600 and 2000 p.p.m. of the salt.

b. Bactericidal tests

The solutions prepared in a) were tested for bactericidal activity in the same manner as in Example 6. Control examples were provided using the same concentrations of chlorhexidine digluconate.

Results

The results are shown in Table IV below.

TABLE IV

Final concentration of bactericide p.p.m.	200	400	600	800	1000
Bactericide					

TABLE IV-Continued

Final concentration of bactericide p.p.m.	200	400	600	800	1000
Tri(chlorhexidine) DI(DTPA)	u/c	26.36	133	0	0
Chlorhexidine Digluconate (control)		4624	u/c	318	

These results show that tri(chlorhexidine) di(diethylenetriaminopentaacetate) is markedly superior to chlorhexidine digluconate as a bactericide.

EXAMPLE 10: Mono(chlorhexidine) di(hydroxyethylaminoacetate).

a. Preparation of the compositions

Solid mono(chlorhexidine) di(hydroxyethylaminoacetate), prepared as in Example 5, was dissolved in standard hard water (W.H.O. formulation), to yield solutions containing 800, 1200, 1600 and 2000 p.p.m. of the salt.

b. Bactericidal tests

The solutions produced in a) were tested for bactericidal activity in the same manner as in Example 6. Control examples were provided using the same concentrations of chlorhexidine digluconate.

Results

The results are shown in Table V below.

TABLE V

Final concentration of bactericide di(hydroxyethylaminoacetate) p.p.m.	400	600	800	1000
Bactericide				
Mono(chlorhexidine) Di(hydroxyethylaminoacetate)	600	35	0	0
Chlorhexidine Digluconate (control)		1200	520	308

These results show that mono(chlorhexidine) di(hydroxyethylaminoacetic acid) is markedly superior to chlorhexidine digluconate as a bactericide.

PART III: COMPOSITIONS CONTAINING QUATERNARY AMMONIUM COMPOUNDS

EXAMPLE 11: Mono(chlorhexidine) mono(HEDTA) /Cetrimide

a. Preparation of the composition

14.3 G of chlorhexidine, 20.4 g of cetyltrimethyl ammonium bromide and 7.8 g of hydroxyethylmethylenediaminetriacetic acid (HEDTA) were allowed to react in 57.5 g water under agitation, until a clear solution was obtained which was dilutable with water in all concentrations and contained a mixture of mono(chlorhexidine) mono(hydroxyethylmethylenediaminetriacetate) and cetyltrimethylammonium bromide.

b. Bactericidal tests (Antiseptic Test)

The solution obtained in a) was tested for bactericidal activity according to British Standard Specification 2462.

As stated above, a particularly stringent anti-bacterial test is against the highly resistant gram negative bacterium *Pseudomonas pyocyannea* in the presence of hard water and organic matter. The essential details of the test are set out below:

i. Materials

Nutrient Broth

Nutrient Broth No. 2 is used as in Example 6 above.

Inactivator

5 Nutrient Broth with the addition of 0.5 percent of lecithin (ex ovo) (= a substance derived from egg yolks, being a compound of choline, glycerol, phosphoric acid and various fatty acids) and 2 percent Lubrol W. (= a proprietary brand of an anhydrous condensation product of a long chain fatty alcohol and ethylene oxide). The pH is adjusted if necessary to 7.2.

Bacteria

Pseudomonas aeruginosa (pyocyanea) N.C.T.C. No.

15 6749 maintained on nutrient agar.

ii. Preparation of Culture

A culture from agar of the organism was prepared in nutrient broth, and incubated at 37°C for 24 hours. Daily subcultures were continued, and cultures between the third and seventh generation were used for the test. The broth culture of *Pseudomonas pyocyannea* was filtered aseptically before use, or shaken, allowed to settle for 15 minutes, and the supernatant liquor used for the test.

25 Culture dilution

One part of the broth culture was diluted with 24 parts of distilled water, i.e. 4 ml. broth culture + 96 ml of distilled water. The average count of bacteria in such 30 a dilution would be 5×10^7 organisms per ml.

Method of Test

Serial double strength dilutions of the anti-bacterial compositions to be tested are made in distilled water, and 2.5 ml transferred into sterile test tubes. Starting at 35 zero time 2.5 ml of the diluted bacterial culture suspensions containing 20 percent of bovine serum were added to each test tube containing an anti-bacterial composition under test. After 5 minutes a loop full (about 0.1 ml) of the bacterial culture/anti-bacterial composition mixture from each tube was transferred to 40 10 ml of the inactivator broth medium in a new series of sterile test tubes. After a total of 10 minutes another loop was transferred from the original bacterial culture/anti-bacterial composition mixture to a similar new set of tubes containing inactivator broth medium. The inactivator stopped the further action of the anti-bacterial and allowed the bacteria to grow again.

45 All the tubes containing the inactivator broth seeded with bacteria transferred on the loop were incubated at 37°C for 48 hours, and examined for bacterial growth. The result was recorded as positive where growth occurred and negative where no growth occurred. The lowest concentration of antibacterial which gave a negative result after the 5 minute contact test can be seen and verified by the 10 minute contact test, and that concentration was recorded as being the killing dilution for that particular bactericide. The negative result

55 60 tubes are subcultured into nutrient broth to ensure that the bacteria really have been killed, and that bacterios-tasis has not taken place.

The results are expressed as the minimum concentration tested giving a 100 percent kill in five minutes at 22°C.

65 By way of example, the average of numerous tests on Benzalkonium Chloride B.P.C. was as follows:

15

Dilution	Transfer in minutes	
	5	10
1-666 = 1,500 ppm	—	—
1-1000 = 1,000 ppm	+	—
1-1333 = 750 ppm	+	—
1-2000 = 500 ppm	+	+

Concentration giving 100 percent kill = 1,500 ppm. It will be appreciated that the true figure may be anywhere between 1,000 ppm and 1,500 ppm, and thus the killing concentrations given in the following tests are subject to errors of substantially the same magnitude.

One can determine the concentration of the various mixtures made according to the Examples (expressed in terms of parts per million of total organic material [bis-biguanide plus quaternary ammonium compound + aminocarboxylic acid]) and hence, knowing the relative quantities of the components, one can calculate from the Antiseptic Test results the killing dilution in terms of bis-biguanide and/or quaternary ammonium compound.

Results

The results are shown in Table VI below. To provide controls, the killing dilutions of tests on chlorhexidine digluconate and a typical quaternary ammonium sequestrate mono(myristyldimethylbenzylammonium) mono(HEDTA) were also tested.

TABLE VI

Bactericide	Killing Dilutions			
	(a) ppm bis-biguanide base	(b) ppm quaternary ammonium compound (cation + anion)	(c) ppm acid	ppm organic material (a)+(b)+(c)
Composition of this invention	60	90	30	180
Chlorhexidine Digluconate (control)	200	—	150	350
QAC sequestrate (control)	—	1060	440	1500

These results show the superiority of the composition of the present invention to chlorhexidine digluconate and the QAC sequestrate as a bactericide.

EXAMPLE 12: Mono(chlorhexidine) mono(HEDTA) /Cetrimide

A solution of 12.6 g of chlorhexidine, 18.8 g of cetyltrimethylammonium bromide and 9.2 g of hydroxyethylethylenediaminetriacetic acid in 300 g water was heated to 60°C and mixed with 8 parts of glycerol under agitation. A completely gelatinized mixture was obtained which could be used for application to the skin.

EXAMPLE 13: Mono(chlorhexidine) mono(HEDTA) /Cetrimide

a. Preparation of the composition

A solution was prepared from 17.6 g of chlorhexi-

55

dine, 18.2 g of cetyltrimethylammonium bromide and 11.2 g of hydroxyethylethylenediaminetriacetic acid in 53 g water.

b. Bactericidal Tests

The composition prepared in a) was tested for bactericidal effects in the same manner as in Example 11. The results are shown in Table VII below.

TABLE VII

Bactericide	Killing Dilution			
	(a) ppm bis-biguanide base	(b) ppm quaternary ammonium compound	(c) ppm acid	ppm organic material (a)+(b)+(c)
Composition prepared in a)	75	75	45	195

These results should be compared to those given for chlorhexidine digluconate and QAC sequestrate in Table VI above, whereupon it will be seen that the composition of this invention is markedly superior as a bactericide to both these conventional agents.

EXAMPLE 14:

a. Preparation of the composition

15 g of the di-(myristyldimethylbenzyl ammonium) salt of HEDTA and 8 g of chlorhexidine were dissolved

25

in 77 g water, and an aqueous solution was obtained.

b. Bactericidal tests

The composition obtained in a) was tested for bactericidal activity in the same manner as in Example 11, and the results are shown in Table VIII below.

TABLE VIII

Bactericide	Killing Dilution			
	(a) ppm bis-biguanide base	(b) ppm quaternary ammonium compound (cation + anion)	(c) ppm acid	ppm organic material (a)+(b)+(c)
Composition prepared in a)	53	71	29	153

65

These results should be compared to those given for chlorhexidine digluconate and QAC sequestrate in Table VIII above, whereupon it will be seen that the composition of this invention is markedly superior as a bactericide to both these conventional agents.

**EXAMPLE 15: Mono(chlorhexidine) di(HEDTA)
di(myristyldimethylbenzylammonium)
mono(HEDTA)**

Myristyldimethylbenzylammonium hydroxide was prepared using essentially the following method. 367.5 Gm (1 mole) of myristyldimethylbenzylammonium chloride was dissolved in the smallest possible quantity of isopropyl alcohol. A saturated solution of 56 gm (1 mole) of potassium hydroxide in absolute ethanol was added under agitation. After a few hours, the precipitate of potassium chloride which had formed was filtered off and washed with isopropyl alcohol, the washings being returned to the main solution. The resultant alcoholic solution contained myristyldimethylbenzylammonium hydroxide. This solution was divided into 10 aliquots each containing 0.1 mole (34.9 gm) of the quaternary ammonium hydroxide. The mono(myristyldimethylbenzylammonium) salt of hydroxyethylethylenediaminetriacetic acid was prepared by taking one of the aliquots containing 0.1 mole of myristyldimethylbenzylammonium hydroxide and adding 27.8 gm (0.1 mole) of a solution of HEDTA in water, then making the solution up to 418 ml. This 15 percent w/w solution of the quaternary ammonium sequestrate contained 8.18 percent of the quaternary ammonium cat-

**EXAMPLE 16: Mono(chlorhexidine)
mono(HEDTA)(Myristyldimethylbenzylammonium
hydroxide)**

a. Preparation of the composition

By the same method as in Example 15, di(myristyldimethylbenzylammonium) mono(hydroxyethylethylenediaminetriacetate) was prepared by using 0.1 mole of the quaternary ammonium hydroxide and 13.9 gm (0.05 mole) of HEDTA, and this was made up to 314 ml to give a 15 percent w/w solution containing 10.6 percent of quaternary ammonium cation and 4.4 percent of dibasic HEDTA anion.

By taking 2 ml of this 15 percent di(myristyldimethylbenzylammonium) mono(hydroxyethylethylenediaminetriacetate) and 0.16 gm of chlorhexidine base a 1:1 compound of chlorhexidine to dibasic HEDTA anion was prepared, that is mono(chlorhexidine) mono(hydroxyethylethylenediaminetriacetate).

The result was a clear solution which could be further diluted to a clear solution containing 1060 ppm quaternary ammonium cation, 440 ppm HEDTA anion and 800 ppm of chlorhexidine.

b. Bactericidal tests

The composition prepared in a) above was tested for bactericidal activity in the same manner as in Example 11 above. To provide controls, the killing dilutions of chlorhexidine digluconate and di(myristyldimethylbenzylammonium) mono(hydroxyethylethylenediaminetriacetate) were also tested. The results are shown in Table IX below.

TABLE IX

Bactericide	Killing Dilutions						
	ppm Quaternary Ammonium compound	ppm Quaternary Ammonium cation	ppm HEDTA anion	ppm Chlorhexidine	ppm of active ingredients + Quaternary ammonium cation	% Chlorhexidine by weight of active ingredients	Total organic matter p.p.m.
Quaternary Ammonium sequestrate	1500	1060	440	0	1060	0	1500
Composition of this invention	100	71	29	53	124	44	153
Chlorhexidine digluconate	0	0	0	200	200	100	350

ion and 6.82 percent of the monobasic HEDTA anion.

To prepare the mono(chlorhexidine) di(HEDTA) salt it is necessary to add chlorhexidine in the molecular weight ratio of 505 parts chlorhexidine to 2×278 parts HEDTA measured in terms of free acid or 2×277 measured in terms of monobasic anion.

Thus 0.124 gm of chlorhexidine was dissolved in 2 ml of the 15 percent solution of mono-myristyldimethylbenzylammonium mono(HEDTA) salt, to give a clear solution of the required mono(chlorhexidine) di(hydroxyethylethylenediaminetriacetate).

This solution could be diluted with distilled water to give for example a solution containing 820 ppm of quaternary ammonium cation, 682 ppm of monobasic HEDTA anion and 620 ppm of chlorhexidine.

These results show the superiority of the composition of this invention to both the quaternary ammonium sequestrate and chlorhexidine digluconate as a bactericide.

**EXAMPLE 17: Mono(chlorhexidine)
di(HEDTA)/Myristyldimethylbenzylammonium
hydroxide/HEDTA salt**

a. Preparation of the composition

By the same method as in Example 16, mono(chlorhexidine) di(hydroxyethylethylenediaminetriacetate), containing 1 molar proportion of chlorhexidine to 2 molar proportions of HEDTA anion, was prepared by taking 2 ml of the 15 percent solution of di(myristyldimethylbenzylammonium) mono(hydroxymethyle-

thylene diamine triacetate) and adding 0.08 gm of chlorhexidine. The product was a clear solution which could be further diluted with water.

b. Bactericidal tests

The composition prepared in a) was tested for bactericidal activity in the same manner as in Example 11. The results are shown in Table X below.

EXAMPLE 19: Mono(chlorhexidine) di(HEDTA)/Didecyldimethylammonium chloride

a. Preparation of the composition

A series of mixtures of chlorhexidine di(hydroxyethylenediaminetriacetate) and didecyldimethylammonium chloride were made.

TABLE X

	Killing Dilution					
	ppm Quaternary Ammonium compound	ppm Quaternary Ammonium cation	ppm HEDTA anion	ppm Chlorhexidine	ppm of active ingredients + Quaternary ammonium cation	Total organic matter
Composition of a) above	400	283	117	108	391	508

By comparing these results with those for the quaternary ammonium sequestrate and chlorhexidine digluconate given in Table IX above, it will be seen that the composition of the present invention is markedly superior to both these conventional bactericides.

EXAMPLE 18: Mono(chlorhexidine)mono-and di(HEDTA)/di(myristyldimethylbenzylammonium) mono(HEDTA)

a. Preparation of the composition

Using exactly the same method as in Example 16, compositions were prepared from the 15 percent w/w solution of di(myristyldimethylbenzylammonium) mono(hydroxyethylenediaminetriacetate) and chlorhexidine base which corresponded to mixtures of the mono(chlorhexidine) mono(HEDTA) salt and the mono(chlorhexidine) di(HEDTA) salt with excess of the di(quaternary ammonium) mono(HEDTA) salt.

Whereas in Example 16, the mono(chlorhexidine) mono (HEDTA) salt was made from 15 percent quaternary ammonium HEDTA salt and 8 percent chlorhexidine, and in Example 17 the mono (chlorhexidine) di(HEDTA) salt was made from 15 percent quaternary ammonium salt + 4 percent chlorhexidine, in this Example the following mixtures were prepared:

- 15% Quaternary HEDTA + 1% chlorhexidine (i.e. less than 1:2)
- 15% Quaternary HEDTA + 2% chlorhexidine (i.e. less than 1:2)
- 15% Quaternary HEDTA + 6% chlorhexidine (i.e. more than 1:2 but less than 1:1)

b. Bactericidal tests

The compositions prepared in a) above were tested for bactericidal activity in the same manner as in Example 11. The results are shown in Table XI below.

The chlorhexidine di(HEDTA) salt can be made by the method of Example 2 and the solid redissolved in water, but for this Example a 0.2 percent w/w solution of the salt was made up directly by dissolving 0.954 grammes of chlorhexidine and 1.046 grammes of HEDTA in 1000 ml of distilled water.

Didecyldimethylammonium chloride is commercially available in the form of a concentrated solution containing 50 percent of the salt and 50 percent of water. A 0.2 percent solution of the salt was made up by dissolving 4.0 gm of this concentrate in 1000 ml of distilled water.

These two solutions were then mixed in the following proportions by volume:

	Solution	Quaternary ammonium salt	Chlorhexidine di(HEDTA)
A. (control)	100%	0	
B.	90%	10%	
C.	70%	30%	
D.	50%	50%	
E.	30%	70%	
F.	10%	90%	
G.	0	100%	

b. Bactericidal Tests

The solutions A to G prepared in a) above were tested for bactericidal activity in the same manner as in Example 11 above. The killing dilution of chlorhexi-

TABLE XI

	ppm Quaternary Ammonium compound	ppm Quaternary Ammonium cation	ppm HEDTA anion	ppm Chlorhexidine	ppm of active ingredients + Quaternary ammonium cation	% Chlorhexidine by weight of active ingredients	Total organic matter
Solution							
a	1000	707	293	67	774	8.6	1067
b	500	354	146	67	421	16	567
c	150	106	44	60	166	36	210

By comparing these results with those for the quaternary ammonium sequestrate and chlorhexidine digluconate given in Table IX above, it will be seen that the compositions of the present invention are markedly superior to both these conventional bactericides.

dine digluconate was also tested as a control. The results are shown in Table XII below, and are also plotted graphically in FIG. 1 of the accompanying drawings.

TABLE XII

Solution	Killing Dilutions					
	p.p.m. total QAC and chlorhexidine di (HEDTA)	p.p.m. Chlorhexidine	p.p.m. HEDTA anion	p.p.m. ammonium cation	p.p.m. chloride anion	p.p.m. gluconate
A (control)	750	0	0	675	75	0
B	500	24	26	405	45	0
C	275	39	44	173	0	0
D	275	64	71	124	14	0
E	175	58	65	47	5	0
F	200	86	94	18	2	0
G	200	95	105	0	0	0
chlorhexidine digluconate (control)	400	228	0	0	0	172

These results show not only the superiority of mono (chlorhexidine) di(HEDTA) to chlorhexidine diglutonate as a bactericide but also the synergism which occurs on mixing mono (chlorhexidine) di(HEDTA) and didecyldimethylammonium chloride. If the bactericidal activities of the two compounds were simply additive, the test results would be along the line A, but in fact all the observations lie on a curve B lying wholly below A. Thus, the bactericidal properties of the mixtures are greater than would be expected from the properties of the single components, and thus the mixtures are synergistic.

TABLE XIII
Killing Dilutions

Solution	Total Concentration of bactericide ppm	Chlorhexidine cation ppm	HEDTA anion ppm	Quaternary ammonium cation ppm	Chloride anion ppm
A	300	143	157	0	0
B	400	143	157	92	8
C	500	119	131	230	20
D	>1000	119	131	690	60
E (control)	>>1000	0	0	920	>>80

It will be seen from these results that not only is mono(chlorhexidine) di(HEDTA) a much better bactericide than Hyamine but also that mixtures of the chlorhexidine sequestrate and the quaternary ammonium compound exhibit synergism—as in Example 19, the curve B of the killing dilutions of mixtures of the two compounds always lies below the straight line A which shows the results which would be obtained if the bactericidal effects of the two compounds behaved additively (the tests indicated that the killing dilution of the quaternary ammonium compound alone was about 2500 ppm and the line A is drawn on this basis).

EXAMPLE 20: Mono(chlorhexidine) di(HEDTA)/Hyamine 10X

45

a. Preparation of the composition

A 0.2 percent w/w solution of chlorhexidine di(hydroxyethylenediaminetriacetate) was prepared by dissolving 0.954 gm of chlorhexidine base and 1.046 gm of HEDTA in 1000 ml of distilled water and a 0.2 percent w/w solution of Hyamine 10X (a United States trade name for di-isobutylcresoxyethoxyethylidemethylbenzylammonium chloride) in distilled water was also made up.

The two solutions were then mixed in the following ratios:

Solution	Mono(chlorhexidine) di(HEDTA)	Hyamine 10X
A	100%	0%
B	75%	25%
C	50%	50%
D	25%	75%
E (control)	0%	100%

In each case, clear, stable solutions resulted.

b. Bactericidal Tests

The compositions prepared in a) were tested for bactericidal activity in the same manner as in Example 11.

EXAMPLE 21: Mono(chlorhexidine) di(HEDTA)/Hyamine 1622

a. Preparation of the composition

The 0.2 percent w/w solution of chlorhexidine di(HEDTA) prepared in Example 20 was mixed with a 0.2 percent w/w solution of Hyamine 1622 (a United States trade name for diisobutylphenoxyethoxyethylidemethylbenzylammonium chloride) in the following ratios:

Solution	Mono(chlorhexidine) di(HEDTA)	Hyamine 1622
A	100%	0%
B	75%	25%
C	50%	50%
D	25%	75%
E (control)	0%	100%

60

In each case, clear, stable solutions resulted.

b. Bactericidal Tests

The compositions prepared in a) were tested for bactericidal activity in the same manner as in Example 11.

The results obtained are shown in Table XIV below, and are also presented graphically in FIG. 3 of the accompanying drawings.

TABLE XIV

Solution	Total Concentration of bactericide ppm	Chlorhexidine cation ppm	HEDTA anion ppm	Quaternary ammonium cation ppm	Chloride anion ppm
A	250	119	131	0	0
B	500	177	198	115	10
C	600	143	157	276	24
D	>1000	>119	>131	>690	>60
E (control)	>>1000	0	0	>>920	>>80

It will be seen from these results that not only is mono(chlorhexidine) di(HEDTA) a much better bactericide than Hyamine 1622, but also that mixtures of the chlorhexidine sequestrate and the quaternary ammonium compound exhibit synergism—as in Example 19, the curve B of the killing dilutions of mixtures of the two compounds always lies below the straight line A which shows the results which would be obtained if the bactericidal effects of the two compounds behaved additively (the tests indicated that the killing dilution of the quaternary ammonium compound alone was about 2500 ppm and the line A is drawn on this basis).

EXAMPLE 22: Mono(chlorhexidine) di(HEDTA)/Cetylpyridinium chloride

a. Preparation of the compositions

The 0.2 percent w/w solution of chlorhexidine di(HEDTA) prepared in Example 20 was mixed with 0.2 percent w/w solution of cetylpyridinium chloride in the following ratios.

Solution	Mono(chlorhexidine) di(HEDTA)	Cetylpyridinium chloride
A	100%	0%
B	75%	25%
C	50%	50%
D	25%	75%
E (control)	0%	100%

In each case, clear, stable solutions resulted.

20

25

30

EXAMPLE 23: Chlorhexidine HEDTA sequestrates/coco-dihydroxyethyl-benzyl ammonium HEDTA mixtures

a. Preparation of the compositions

1.68 Gm of a 50 percent solution of coco-di(hydroxyethyl)-benzylammonium chloride and 0.277 gm of hydroxyethylenediaminetriacetic acid were made up into 100 ml of solution (solution I) with distilled water. Thus the molar ratio of ammonium cation to HEDTA anion in the solution was 2:1. A similar solution (solution II) was prepared which contained, in addition 0.42 gm of chlorhexidine. These two solutions were then mixed in the following proportions:

Solution	Resultant solution				
	Parts by weight solution I	Parts by weight solution II	% by weight chlorhexidine	% by weight ammonium cation	% by weight HEDTA anion
A	1	0	0	0.769	0.277
B	5	1	0.07	0.769	0.277
C	2	1	0.14	0.769	0.277
D	1	1	0.21	0.769	0.277
E	1	2	0.28	0.769	0.277
F	0	1	0.42	0.769	0.277

b. Bactericidal tests

The compositions prepared in a) above were tested for bactericidal activity in the same way as in Example 11. The results obtained are shown in Table XV below, and are also presented graphically in FIG. 4 of the accompanying drawings.

45

50

TABLE XV

Solution	Total Concentration of bactericide ppm	Chlorhexidine cation ppm	HEDTA anion ppm	Quaternary ammonium cation ppm	Chloride anion ppm
A	300	143	157	0	0
B	400	143	157	90	10
C	600	143	157	270	30
D	600	72	78	405	45
E (control)	>1000	0	0	>900	>100

It will be seen from these results that not only is mono(chlorhexidine) di(HEDTA) a much better bactericide than cetylpyridinium chloride, but also that mixtures of the chlorhexidine sequestrate and the quaternary ammonium compound exhibit synergism—as in Example 19, the curve B of the killing dilutions of mixtures of the two compounds always lies below the straight line A which shows the results which would be obtained if the bactericidal effects of the two compounds behaved additively (the tests indicated that the killing dilution of cetylpyridinium chloride alone was about 500 ppm and the line A is drawn on this basis).

TABLE XVI

Solutions	Total bactericide ppm	Killing Dilutions			
		ppm of quaternary ammonium cation	ppm HEDTA anion	ppm chlorhexidine cation	ppm gluconate
A	750			0	0
B	704			44	0
C				62	0
D	400			67	0
E	380			80	0
F	350	198	52	100	0
Chlorhexidine digluconate	660	0	0	376	284

These results show the superiority of compositions containing the quaternary ammonium cations, HEDTA anions and chlorhexidine cations to both chlorhexidine digluconate and quaternary ammonium sequestrates as bactericides.

EXAMPLE 24: Chlorhexidine HEDTA sequester/Dioctyldimethylammonium chloride mixtures

a. Preparation of the composition

Using the same technique as in Example 23, the following solutions were prepared:

Solution I

Dioctyldimethylammonium chloride	0.65 gm
HEDTA	0.28 gm
Distilled water to	100 ml

Solution II

Dioctyldimethylammonium chloride	0.64 gm
HEDTA	0.28 gm
Chlorhexidine	0.5 gm
Distilled water to	100 ml

These two solutions were then mixed in the following proportions:

Solution	Resultant Solution				
	Parts by weight solution I	Parts by weight solution II	% by weight chlorhexidine	% by weight ammonium cation	% by weight HEDTA anion
A	1	0	0	0.569	0.28
B	7	1	0.063	0.569	0.28
C	3	1	0.125	0.569	0.28
D	1	1	0.25	0.569	0.28
E	1	2	0.33	0.569	0.28
F	0	1	0.5	0.569	0.28

b. Bactericidal tests

The compositions produced in a) above were tested for bactericidal activity in the same manner as in Example 11. To provide a control, chlorhexidine digluconate was also tested. The results are shown in Table XVII below.

TABLE XVII

Solution	Killing dilutions				
	total ppm bactericide	ppm of quaternary ammonium cation	ppm HEDTA anion	ppm chlorhexidine cation	ppm gluconate anion
A	750	500	250	0	0
B	483	300	150	33	0
C	516	300	150	66	0
D	421	217	108	96	0
E	423	200	100	123	0
F	398	167	83	148	0
Chlorhexidine digluconate	660	0	0	376	284

15

These results show the superiority of compositions containing the quaternary ammonium cations, HEDTA anions and chlorhexidine cations to both chlorhexidine digluconate and quaternary ammonium sequestrates as bactericides.

EXAMPLE 25: Chlorhexidine HEDTA sequester/Cetyltrimethyl-ammonium bromide mixtures

25 As shown above mono(chlorhexidine) mono (HEDTA) is soluble in water at 20° C to the extent of only 0.2 percent, and the mono(chlorohexidine) di (HEDTA) is soluble to the extent of only about 0.3 percent. This is a serious disadvantage from the commercial point of view, and this Example shows that the solubility of these chlorhexidine sequestrates can be greatly increased by adding cetyltrimethylammonium bromide, thus producing a commercially superior product.

35 Mixtures of chlorohexidine and HEDTA were added to water and cetyltrimethylammonium bromide (Cetrimide) was added until a clear solution was obtained.

Alternatively, the solutions can be prepared by adding the solid chlorohexidine sequestrate to water and adding the ammonium compound until dissolution takes place.

In this way, the following solutions were prepared:

55	Solution	Chlorhexidine cation % by weight	HEDTA anion % by weight	Molar ratio chlorhexidine HEDTA	Cetyltrimethyl ammonium bromide % by weight
	A	14.0	7.7	1:1	20.0
	B	18.0	9.2	1:1 + excess	17.6
	C	7.2	7.1	1:2	20.7
	D	5.5	8.3	1:2 + excess	11.1

65 All these solutions were clear and stable.

b. Bactericidal tests

The solutions produced in a) were tested for bactericidal activity by the Anti-septic Test described in Example 11 above. These tests employed

Pseudomonas pyocyanea in:-

- A. Standard hard water (W.H.O.formulation - described in Example 12 above), without the addition of serum;
 B. Distilled water with the addition of 10% bovine serum; and
 C. Standard hard water (W.H.O formulation), with the addition of 10% of bovine serum.

To provide a control, chlorhexidine digluconate was also tested. The results are shown in Table XVIII below.

TABLE XVIII

Killing dilutions				
Solution	ppm chlorhexidine cation	ppm HEDTA anion	ppm gluconate	ppm Cetrimide
A	80	45	0	114
B	200	100	0	289
C	100	100	0	288
D	80	120	0	162
Chlorhexidine digluconate	570	0	430	0
B) Distilled water, 10% serum				
Solution	ppm chlorhexidine cation	ppm HEDTA anion	ppm gluconate	ppm Cetrimide
A	130	70	0	185
B	100	50	0	145
C	50	50	0	144
D	60	90	0	121
Chlorhexidine digluconate	285	0	215	0
C) Standard hard water, 10% serum				
Solution	ppm chlorhexidine cation	ppm HEDTA anion	ppm gluconate	ppm Cetrimide
A	320	180	0	456
B	760	390	0	1097
C	390	380	0	1124
D	200	300	0	405
Chlorhexidine digluconate	1,145	0	855	0

These results show that, by incorporating cetyltrimethyl-ammonium bromide and a sequestering aminocarboxylic acid into compositions containing chlorhexidine, the amount of chlorhexidine needed to produce a given bactericidal effect can be greatly reduced. In view of the fact that HEDTA and cetrimide are both far, far cheaper than chlorhexidine, this enables an enormous reduction in the cost of the bactericidal composition needed to produce a given effect. Alternatively, the efficacy of the bactericidal composition which can be produced at any given cost may be greatly increased.

EXAMPLE 26: Chlorhexidine DTPA Sequestrate/Cetrimide mixtures.

a. Preparation of the compositions

Using the same method as in Example 25, the following chlorhexidine DTPA sequestrate/cetrimide mixtures were prepared:-

Solution	Chlorhexidine cation % by weight	DTPA anion % by weight	Cetrimide % by weight
A	10.5	7.5	15.0
B	13.4	6.5	19.5

The resulting solutions were clear.

b. Bactericidal tests.

The solutions prepared in a) were tested for bactericidal activity in the same manner as in Example 25, in:-

- A. Standard hard water (W.H.O. formulation), with no serum:

- B. Distilled water, with 10 percent of bovine serum; and

- C. Standard hard water (W.H.O formulation) with 10 percent of bovine serum.

To provide a control, chlorhexidine digluconate was also tested. The results are shown in Table XIX below.

TABLE XIX

Killing dilutions				
A) Standard hard water, no serum	Solution	ppm chlorhexidine cation	ppm DTPA anion	ppm gluconate
A	60	40	0	86
B	67	33	0	98
Chlorhexidine digluconate	570	0	430	0
B) Distilled water, 10% serum	Solution	ppm chlorhexidine cation	ppm DTPA anion	ppm gluconate
A	90	60	0	129
B	100	50	0	147
Chlorhexidine digluconate	285	0	215	0
C) Standard hard water, 10% serum	Solution	ppm chlorhexidine cation	ppm DTPA anion	ppm gluconate
A	300	200	0	430
B	670	330	0	980
Chlorhexidine digluconate	1145	0	855	0

In the same way as in Example 25, these results show that the efficacy of a bactericidal composition containing chlorhexidine can be greatly increased by adding cetrimide and DTPA, with consequent savings in cost.

Similar results were obtained with chlorhexidine NTA sequestrate/cetrimide mixtures.

EXAMPLE 27: Efficacy of compositions of this invention against various bacteria

In order to show that the efficacy of the compositions of this invention is not restricted to Pseudomonas pyocyanea, solution A from Example 25 and solution A from Example 26 were tested with chlorhexidine digluconate, for their killing power against a wide range of

bacteria. The tests were conducted in the same manner as in Example 11, in distilled water containing 10 percent of bovine serum, and the bacteria used were as follows:-

1. *Pseudomonas pyocyanea* N.C.T.C. 6749
2. *Proteus vulgaris* N.C.T.C. 4635
3. *Salmonella typhi* N.C.T.C. 3390
4. *Escherichia coli* N.C.T.C. 8196
5. *Staphylococcus aureus* N.C.T.C. 3750

These results show that the compositions of this invention are markedly superior to chlorhexidine digluconate against a wide range of bacteria.

EXAMPLE 28:

To confirm the results with *E.Coli* shown in Example 27, tests of the bactericidal properties of compositions of this invention against *E.coli* were carried out by the method of British Standard 3286:1960 described above in standard hard water (W.H.O formulation) containing 10 percent of bovine serum. The solutions used were as follows, chlorhexidine digluconate being provided as a control:-

Solution	% by weight chlorhexidine cation	% by weight HEDTA anion	% by weight DTPA anion	% by weight NTA anion	% by weight gluconate anion	% weight Cetrimide
A	13.0	7.2	0	0	0	18.9
B	13.6	0	6.5	0	0	11.3
C	14.4	0	0	5.1	0	15.4
Chlorhexidine digluconate (control)	11.4	0	0	0	8.6	0

The compositions were tested at concentrations equivalent to 100, 150, 200, 250, 300, 400, 500, 600, and 800 p.p.m. of chlorhexidine sequester or digluconate. The results, which are shown in Table XXI below, are expressed in terms of the number of survivors per million bacteria inoculated.

TABLE XXI

Dilution in ppm chlorhexidine sequester	Solution												Chlorhexidine digluconate (control)	
	A			B			C							
	Test 1	Test 2	Test 3	Test 1	Test 2	Test 3	Test 1	Test 2	Test 3	Test 1	Test 2	Test 3		
100	—	—	—	—	—	—	u/c	—	—	—	—	—	—	
150	—	—	137	—	24	85	432	36	u/c	—	—	—	—	
200	190	78	27	260	0	30	0	—	0	—	—	—	—	
250	0	—	—	—	—	—	0	—	0	—	—	—	—	
300	0	0	0	113	0	0	0	44	0	—	—	u/c	—	
400	0	0	0	0	0	0	0	0	0	—	133	162	—	
500	0	0	0	0	0	0	0	0	0	174	—	110	—	
600	0	0	0	0	0	0	0	0	0	100	0	23	—	
800	0	0	0	0	0	0	0	0	0	0	0	0	—	

u/c — survivors too numerous to be counted

These results confirm that the compositions of this invention are markedly superior as bactericides against *E.coli* as compared with chlorhexidine digluconate.

The results obtained are shown in Table XX below.

We claim:

1. A salt selected from the group consisting of: mono-chlorhexidine nitrilotriacetate, tri(chlorhexidine) di(diethylenetriaminepentaacetate) mono-chlorhexidine N,N-dihydroxyethylaminoacetate, mono-chlorhexidine N-hydroxyethylthylenediaminetriacetate, and mono-chlorhexidine di[N-hydroxyethylthylenediaminetriacetate].
